Patented Dec. 26, 1961

192,002

HANDLE FOR FAUCETS OR THE LIKE

Stephen A. Young, Delphi, Ind.

Filed Jan. 13, 1958, Ser. No. 49,218

Term of patent 14 years

(Cl. D91—3)

FIG. 3

FIG. 4

FIG. 5

FIG. 6

FIGURE 1 is a top plan view of a handle for faucets embodying my new design.

FIGURE 2 is a side elevation thereof.

FIGURE 3 is an end elevation thereof looking from the left hand end of FIGURE 1.

FIGURE 4 is an end view thereof looking from the right hand end of FIGURE 1.

FIGURE 5 is a bottom plan view thereof.

FIGURE 6 is a sectional view taken through the center of FIGURE 1 on the line 6—6.

I claim:

The ornamental design for a handle for faucets or the like, substantially as shown.
